UNITED STATES PATENT OFFICE

139,473

DESIGN FOR A SMOKE STAND

Urban B. Kronenwetter, St. Marys, Pa.

Application September 21, 1944, Serial No. 115,384

Term of patent 14 years

(Cl. D85—2)

To all whom it may concern:

Be it known that I, Urban B. Kronenwetter, a citizen of the United States, residing at St. Marys, county of Elk, State of Pennsylvania, have invented a new, original, and ornamental Design for a Smoke Stand, of which the following is a specification, reference being had to the accompanying drawing forming a part thereof.

In the drawing—

Fig. 1 is a front perspective view of a smoke stand showing my new design.

Fig. 2 is a rear perspective view thereof.

I claim:

The ornamental design for a smoke stand, substantially as shown.

URBAN B. KRONENWETTER.
